DESIGN FOR A COMBINED KNIFE AND FORK

Jefferson Carroll Phillips, Boulder, Colo.

Application June 22, 1934, Serial No. 52,286

Term of patent 14 years

To all whom it may concern:

Be it known that I, Jefferson Carroll Phillips, a citizen of the United States of America, and a resident of Boulder, Colorado, have invented a new, original, and ornamental Design for a Combined Knife and Fork, of which the following is a specification, reference being had to the accompanying drawing, forming part thereof, in which drawing Fig. 1 is a front view; and Fig. 2 is a side view of a combined knife and fork, showing my new design.

I claim:

The ornamental design for a combined knife and fork, substantially as shown.

In testimony whereof I have signed this specification.

JEFFERSON CARROLL PHILLIPS.
